END CREEPING MECHANISM FOR BAGS

Hans A. Bauer, Chicago, Ill., assignor to B. F. Gump Co., Chicago, Ill., a corporation of Illinois

Application December 24, 1936, Serial No. 117,557

11 Claims. (Cl. 93—6)

This invention relates to an end creasing mechanism for bags.

In bag closing machines, it is necessary to provide end creasing devices that crease and fold inwardly the ends of the neck of the bag so that the side portions of such neck can be brought together or collapsed and later folded. At the present time some bags are made with a "Cellophane" cover or of such material or thickness that it is impossible to crease and fold inwardly the ends of the neck portions of the bag by the devices now in use.

It is, therefore, an object of this invention to provide a creasing and folding mechanism for creasing the end portions of the necks of bags of the class mentioned above. To this end, the invention consists of a pair of cooperating members for each end of the bag that are manipulated for simultaneously engaging and molding the end portions of the neck of a bag to provide the proper creases for a later folding operation.

The invention comprises the novel structure and combination of parts hereinafter described and more particularly pointed out and defined in the appended claims.

In the accompanying drawings, which illustrate a preferred form of this invention and in which similar reference numerals refer to similar features in the different views:

30 Figure 1 is a top plan view of the mechanism involving this invention.

Figure 2 is a side elevational view taken substantially upon the line II—II of Fig. 1.

Figures 3 and 4 are fragmentary front elevational views with parts in section showing the operation of certain parts during the process of creasing a bag partly shown in section.

Figure 5 is an enlarged sectional view taken upon the line V—V of Fig. 1.

40 Figure 6 is a part sectional and part elevational view taken upon the line VI—VI of Fig. 1, with parts omitted.

Figure 7 is an elevational view of a male die constituting one member of the creasing mechanism.

Figure 8 is an elevational view of the female die that cooperates with the male die.

Figure 9 is a part elevation and part sectional view of a pair of cooperating dies with a portion 50 of a bag shown in section therebetween to illustrate the performance thereof.

Figure 10 is a top plan view of a bag with the neck portion folded in and creased according to this invention.

55 It will be understood that the illustrated mech-

anism is one unit of a bag closing machine which has a platform 1 (Fig. 2) for supporting the operating parts of the machine. Upon this platform, there is a bearing standard 2 to the upper end of which the rear end of a lever 3 is pivoted in any suitable manner.

With reference to Fig. 2, it will be observed that the rear portion of the lever 3 is of arcuate form and carries a roller 4 for cooperating with a cam 5 secured upon an operating shaft 6. The forward end of the lever 3 is pivotally connected to a cross head 7 by means of a pin 8.

The cross head 7 is slidably mounted upon a pair of guide posts 9 supported upon the platform 1. Upon each side of the cross head 7 there is pivoted an arm 10 as indicated at 11. It will be noted that the arms 10 are pivoted intermediate their ends and that their rear portions extend into cooperative relation with the cam 5 where they are provided with rollers 12. The cam 5 is provided with suitable side lugs or cam portions 13 and 13a for engaging said rollers for a purpose that will later appear. The center of medial portion of the cross head 7 supports a central head 14 which has laterally projecting arms 15 that support lateral heads 16 as clearly shown in Figs. 1, 3 and 4.

A pair of dies 17 and 18 are supported between each lateral head 16 and the central head 14. The dies 17 which constitute the male dies are provided with laterally extending pins or studs 19 and 20 that slidably extend thru the lateral heads 16 for slidably supporting the same. The female dies 18 are provided with laterally extending arms 21 which are pivoted to a bolt 22 extending thru a suitable bifurcation in the lower end of the head 14. Thus the female dies are susceptible of tilting by gravity upon their pivot bolt 22 as shown in Fig. 4 for the purpose of entering the mouth of a bag. A spring 23 surrounds each bolt 20 between an abutment 24 at the outer ends thereof and the adjacent head 16 for normally urging the dies 17 against the heads 16.

To the top of each die 17 there is secured a bearing block 25 thru which a hollow plunger 26 slidably extends. A coil spring 27 (Fig. 5) is positioned within the hollow plunger and a threaded plug 28 fits in the hollow plunger for adjusting the spring. This plug 28 has a threaded relation with an L-shaped bracket 29 secured to the blocks 25.

The die 18 is formed with a right angle at its upper end as clearly shown in Fig. 5. This angle forms a recess with an upstanding portion or 55

abutment 30 adapted for engagement by the plunger 26 during a creasing operation for righting the die 18 as will later more fully appear.

Movement of the dies 17 into operative relation with the dies 18 is effected by means of the arms 10. To this end, the forward ends of the arms 10 are provided with studs 31 that are directed toward the dies 17. The inner ends of the studs 31 are preferably enlarged as indicated at 32 and they are adapted for engaging pads 33 which may form a part of the dies 17. The heads 16 are cut away as indicated at 34 (Fig. 2) to allow the studs 31 and arms 10 to swing toward each other to bring the dies into cooperative relation.

It is of course necessary for the heads 14 and 16 to fall and rise in a true vertical direction and for this reason a further guiding means is provided for the cross head 7. This guiding means 20 which is best shown in Fig. 2, consists of a guide roll 35 supported upon a bracket 36 extending from the platform 1 and a vertical guide strip 37 attached to the cross head and engaging the roller 35.

25 The confronting faces of each pair of dies or creasing members 17 and 18 may be made of suitable conformation to crease the ends of the neck of the bag as desired. The preferable conformation of the confronting faces of the dies 30 has been illustrated. It will be noted in Figs. 7 to 9 that the male die 17 has its confronting face beveled from a center line 17a forming a forwardly projecting angular portion 17b having converging surfaces, while the female die is provided with a depression 18a having inwardly converging surfaces to receive the angular portion of the die 17 as shown in dotted lines in Fig. 1. Thus the two dies have oppositely converging surfaces which form a V-fold in each 40 end of the neck of the bag when the same are brought together.

The lower portion of the female die 18 is formed with three connected grooves 38, 39 and 40 that form a triangle as shown in Fig. 8, with the apex 45 thereof in the center line of the die. It will be noted in Fig. 9 that this triangular portion slopes downwardly and toward the male die and is in angular relation to the plane of the die.

The male die has a lower triangular portion 17c that is bounded by ribs 41, 42 and 43 that 50 form a triangle for entering the triangular groove formed by the grooves 38, 39 and 40 in the female die. The triangular portion 17c of the male die slopes rearwardly from the front face at the same angle as the sloping triangular portion of 55 the female die.

In operation, as the dies come together, they will fold inwardly the ends of the neck of the bag and the triangular portions will bend inwardly and crease the lower portion of the neck 60 of the bag.

In Fig. 10, there is shown a paper bag 44 with the ends of the neck folded inwardly upon converging lines 45 and in Fig. 9 there is shown the 65 upper portion of the bag with the inwardly sloping creased portion 44a that is formed by the triangular creasing portions of the dies.

During operation of the machine in which this mechanism herein constitutes a unit, the 70 paper bags will pause in proper position beneath the head 14. While a bag is moving into position, the roller 4 will naturally be riding upon the high portion 4a of the cam and the lever 3 and heads 14 and 16 will be in elevated position 75 as shown in dotted lines in Fig. 2. However,

when the bag has come to rest below the head 14, the roller 4 will ride off the high portion of the cam 5 which rotates in counterclockwise direction as indicated by the arrow in Fig. 2 and upon the lower portion 4b, and allow the lever 3 and heads 14 and 16 to descend with the female dies in converging position for entering the mouth of the bag as shown in Fig. 4. At about this time, the wing cam portions 13 and 13a will be brought into operative relation with the rollers 11 and 10 begin the swinging movements of the front ends of the arms 10 toward each other. This movement of the arms 10 will move the male dies 17 toward the female dies and cause the plungers 26 to engage the shoulders 30 on the female dies for 15 righting the same, that is swinging the same to vertical positions. While this righting movement of the female dies is taking place, the roller 4 will be riding upon the portion 4c of the cam 5.

As soon as the roller 4 rides off the cam portion 20 4c and descends upon the cam portion 4d, the lever 3, heads 14 and 16 together with the arms 10 will again descend to bring the parts into proper positions for creasing the ends of the neck of the bag which occurs while the roller 4 is traveling upon the long dwell 4d of the cam. This creasing movement is accomplished when the wing cam portions 13 and 13a swing the forward ends of the arms or levers 10 toward each other sufficiently to bring each pair of male and female 30 dies tightly together to properly crease the end portions of the neck of the bag which are confined between such dies.

As soon as the creasing operation has been completed, the wing portions 13 and 13a of the 35 cam will move away from the lever arms 10 and allow the springs 23 to retract the male dies, allowing the parts to be elevated by the cam 5 which will have rotated to bring the high portion into engagement with the roller 4.

40 From the foregoing, it will be evident that a novel creasing mechanism has been provided for creasing the ends of the neck of bags when "Cellophane" covers are used or when the bags are made of thin or thick material and thus facilitating the later folding of the neck portions and sealing the same. It will further be appreciated that the dies or creasing members have a molding effect that prevents the creased portions from springing back to their original positions.

I am aware that many changes may be made and numerous details of construction may be varied through a wide range without departing from the principles of this invention, and I, therefore, do not purpose limiting the patent granted 55 hereon otherwise than necessitated by the prior art.

I claim as my invention:

1. In an apparatus of the class described, a movable structure, a pair of bag creasing members 60 pivotally supported by said movable structure and adapted for swinging into substantially converging relation for entering the mouth of a bag, a pair of cooperating creasing members slidably supported by said movable structure, and means for moving said last mentioned members for bringing the same into creasing relation with the first mentioned creasing members.

2. In an apparatus of the class described, a movable structure having a central head and lateral heads spaced from said central head, a pair of dies pivoted to said central head, one upon each side thereof and adapted for swinging into converging relation for entering the mouth of a bag, a die slidably mounted adjacent the inner side of 75

each lateral head, and means for actuating said last mentioned dies for bringing the same respectively into operative relation with the first mentioned dies.

5. In an apparatus of the class described, a pair of vertical guide posts, a cross head slidably mounted upon said posts, die supporting means carried by said cross head, movable dies carried by said means, levers pivoted to said cross head and engaging the outermost dies on said means, a cam having a cam surface for actuating said levers and also having a second cam surface, and a lever connected at one end to said cross head and having means for engaging said second cam surface whereby said cross head may be raised and lowered.

4. In an apparatus of the class described, a supporting platform, a standard on said platform, rotary cam means mounted upon said platform and including a plurality of cam surfaces, a lever pivoted to said standard and having a roller in engagement with one of said cam surfaces, a die supporting structure carried by the forward end of said lever, cooperating dies movably mounted upon said structure and levers pivoted to said supporting structure and in engagement with another of said cam surfaces for moving said dies into operative relation.

5. In an apparatus of the class described, a base member, a pair of vertical guide posts rising from said base member, a cross head slidably mounted upon said posts, a pair of dies pivotally mounted upon said cross head for normally swinging into converging relation, for entering the mouth of a bag, a pair of dies slidably mounted upon said cross head, levers pivoted intermediate their ends upon said cross head for actuating said slidable dies, means for raising and lowering said cross head and means for actuating said levers.

6. In an apparatus of the class described, a platform, vertical guide posts rising from said platform, a cross head slidably mounted upon said posts, spaced pendant abutments carried by said cross head, said abutments comprising a central abutment and end abutments, a die pivoted upon each side of said central abutment and adapted for normally swinging into converging relation for entering the mouth of a bag, a die having rods slidably mounted in each end abutment, levers pivoted upon said cross head for actuating said slidable dies, means for actuating said cross head and means for actuating said levers.

7. In an apparatus of the class described, a vertically movable cross head, a pair of dies pivoted to said cross head for swinging by gravity into converging relation for entering the mouth

of a bag, a pair of dies slidably mounted upon said cross head, one upon each side of said pair of dies, levers pivoted intermediate their ends to said cross head and having means at their outer ends for engaging said slidable dies and means for simultaneously actuating said levers for causing said slidable dies to engage said pair of dies and swing the same into parallelism for cooperating therewith for creasing the end walls of a bag.

8. In a bag creasing mechanism, a vertically movable cross head, means for supporting and actuating the same, a pair of dies pivoted to said cross head for normally swinging by gravity into converging relation for entering the mouth of a bag, a pair of slidably mounted dies upon said cross head, one upon each side of said first pair of dies, and means for actuating said slidable dies for causing each one to engage one of said first mentioned dies for first righting the same and then cooperating therewith for creasing the ends of said bag.

9. In a bag creasing mechanism, a vertically movable member, means for supporting and actuating said member, a creasing die pivoted to said member and swingable by gravity to an inclined position for entering the mouth of a bag, a cooperating die slidably mounted upon said member and means for actuating said slidable die for engaging said pivoted die for first righting the same and then cooperating therewith for creasing the wall of said bag.

10. In an apparatus for creasing bags, a movable cross head, means for supporting and guiding the same for movement, a die connected to said member and swingable by gravity to an inclined position for entering the mouth of a bag, a die slidably connected to said cross head and having means at one end for engaging said swingable die for righting the same, and means for actuating said slidable die for moving the same toward said swingable die for first righting the same and then cooperating therewith for creasing the wall of the bag.

11. In an apparatus for creasing bags, a movable cross head, a plurality of creasing dies associated with said cross head and movable into converging relation for entering the mouth of a bag, a plurality of slidably mounted dies connected to said cross head, one upon each side of said creasing dies, means for contemporaneously actuating said slidable dies for bringing the same into engagement with said creasing dies for creasing the wall of the bag, and means for moving said slidable dies out of engagement with said creasing dies.

HANS A. BAUER.
